UNITED STATES PATENT OFFICE.

NATHAN SMITH BOYNTON, OF PORT HURON, MICHIGAN.

DESIGN FOR A BADGE.

SPECIFICATION forming part of Design No. 32,462, dated April 10, 1900.

Application filed February 5, 1900. Serial No. 4,141. Term of patent 7 years.

To all whom it may concern:

Be it known that I, NATHAN SMITH BOYNTON, a citizen of the United States, and a resident of Port Huron, in the county of St. Clair 5 and State of Michigan, have invented and produced a new and original Design for a Badge, of which the following is a specification, reference being had to the accompanying drawing, forming part thereof.

10 My design consists in the unitary article made the subject of illustration, in which the figure shown represents a plan view.

15 A represents a scroll-shaped bar provided with bifurcated ends and a bead-like margin having the representation of a sphere B thereon and a superimposed tent C. From this bar depend connecting-links I I, sus-

pending a disk G, having a peripheral panel E, within the outlines of which is a wreath F. Within the center of the disk is a building provided with domes at the center and corners H, as clearly shown in the drawing. 20

Having described my invention, what I claim as new, and desire to secure by Letters Patent, is—

25 The design for a badge, as herein shown and described.

In testimony whereof I have signed my name to this specification in the presence of two subscribing witnesses.

NATHAN SMITH BOYNTON.
